Primary Examiner — Philip S Hyder*(74) Attorney, Agent, or Firm* — Hodgson Russ LLP(57) **CLAIM**

The ornamental design for a knife insert of a trapper knife assembly, as shown and described.

DESCRIPTION

FIG. 1 is a perspective view of a knife insert of a trapper knife assembly showing our new design;

FIG. 2 is a left side elevation view thereof;

FIG. 3 is a right side elevation view thereof;

FIG. 4 is a top plan view thereof;

FIG. 5 is a bottom plan view thereof;

FIG. 6 is a front elevation view thereof; and,

FIG. 7 is a rear elevation view thereof.

The broken lines in the drawing figures illustrate features of the knife insert of a trapper knife assembly that form no part of the claimed design.

1 Claim, 22 Drawing Sheets(56)
